UNITED STATES PATENT OFFICE.

JOHN A. BELL, OF LATHROP, CALIFORNIA.

PUNCHING-MACHINE.

No. 813,939.

Specification of Letters Patent.

Patented Feb. 27, 1906.

Application filed November 20, 1905. Serial No. 288,131.

To all whom it may concern:

Be it known that I, JOHN A. BELL, a citizen of the United States, residing at Lathrop, in the county of San Joaquin, State of California, have invented certain new and useful Improvements in Punching-Machines; and I do declare the following to be a full, clear, and exact description of the invention, such as will enable others skilled in the art to which it appertains to make and use the same, reference being had to the accompanying drawings, and characters of reference marked thereon, which form a part of this specification.

15 My invention relates to improvements in punching-machines; and my object is to produce such a machine as will enable a person to punch casing-iron, tank-iron, or similar ware readily and effectually and with foot or other power. This object I accomplish by providing an automatic spacer and by such other construction of parts as will appear by a perusal of the following specification and claims.

25 In the drawings similar characters of reference indicate corresponding parts in all the views.

Figure 1 is an end elevation of my improved device. Fig. 2 is a side elevation of the same, partly broken out. Fig. 3 is a view taken on a line *x-x* of Fig. 2. Fig. 4 is a view taken on a line *y-y* of Fig. 2. Fig. 5 is a view taken on a line *z-z* of Fig. 2.

1 designates a work-bench, on top of which 35 is secured an iron plate 2, provided with a punch-die 3. Extending upward from the plate 2 are two standards 4, provided with projecting arms 5 and 6.

7 is a downwardly-projecting arm to which 40 is pivoted a foot-lever 8, and 9 is a spring bearing between said lever and the under side of the bench 1.

10 is a rod pivotally mounted on the foot-lever 8 between the arm 7 and the spring 9 45 and extending upward through the table 1, plate 2, and arms 5 and 6. 11 is a similar rod extending through the arms 5 and 6 and provided with a punch 12, adapted to coact with the punch-hole 3.

50 13 and 15 are lugs forming component parts of the rod 10, and 14 is a similar lug forming a component part of the rod 11 and bearing snugly between the lugs 13 and 15.

16 is a guide provided with an overhanging 55 arm or stripper 17.

18 is a plate secured on the bench 1 in a

line with the plate 2, said plate 18 being provided with a guide 19 and a groove 20, the guide 19 being in a line with the guide 16. In the groove 20 is a plate 21, provided with 60 notches 22, disposed a distance apart equal to the distance desired between the holes punched in the material.

23 is a slot in the bench 1, opening into the slot 20 near the rear of the plate 21.

65

24 is an arm depending from the under side of the bench 1, to which is fulcrumed a link 25, connected at its other end to a lever 26, which is fulcrumed to the foot-lever 8.

27 is a catch pivotally mounted on the link 70 25 and extending through the slot 23, and engaging with the notches 22 and 28 is a wire spring adapted to regulate the position of the said catch 27.

In using the machine the material to be 75 punched is placed under the arm 17 and brought to bear against the end of the plate 21, the notches on which are arranged at the desired distance apart. The operator then presses the foot-lever 8 downward, and this 80

causes the rod 10 to make a downward stroke, and the lug 13, bearing on the lug 14, causes the rod 11 to make a similar downward stroke, which action causes the required hole to be punched, as is apparent. The operator then releases his foot from the lever 8, and the spring 9 then pulls it into position again, which causes the rod 10 to resume its normal position, the lug 15 bearing on the lug 14 and causing the rod 11 to also resume its 90

normal position. The arm 17 acts as a stripper and prevents the material from rising with the punching-rod 11. The downward stroke of the lever 8 pulls on the link 25, which action disengages the catch 27 from 95

the notches 22, and with the rise of the lever 8 the operator bears the material against the head of the plate 21, which causes it to slip to the next notch 22, when the catch 27 again rises and engages with said notch, and the 100 machine is again ready.

I have now entered into a detailed description of the present and preferred embodiment of my device. I do not desire, however, to confine myself to such specific detail, as such 105 modifications may be made in practice as fairly fall within the scope of my claims.

I claim as new and desire to secure by Letters Patent—

1. In a punching-machine a bench, a plate 110 arranged on the top of said bench, two upwardly-extending standards on said plate,

2

two outwardly-extending arms on said standards, a foot-lever secured to the under side of said bench, a spring located between said lever and the under side of said bench, a rod 5 pivotally secured to said lever and extending upward through said bench, plate and arms, a punch-rod bearing in said arms and means for connecting said rods, as specified.

2. In a punching-machine the combination 10 of a bench, an iron plate arranged on the top thereof and provided with a punch-die, two standards extending upward from said plate, two arms extending at right angles to said standards, a foot-lever secured beneath said 15 bench, a spring located between said lever and the under side of said bench, a rod pivotally secured to said lever and extending upward through said bench, plate and arms, two outwardly-extending lugs forming com- 20 ponent parts of said rod between said arms, a punch-rod bearing in said arms and adapted to coact with said die, and a lug forming a component part of said punch-rod and extending between said first-named lugs.

3. In a punching-machine the combination 25 of a punching device, a spacer, consisting of a table, a slotted plate arranged on the top thereof, a slide-plate arranged in said slot and provided with notches at given distances apart, a slot in said table opening into said 30 first-named slot, a lever fulcrumed to the under side of said table, a foot-lever secured to said table, a link connecting said foot-lever to said first-named lever, a spring located between said foot-lever and the under side of 35 said table, a catch pivotally secured to said first-named lever and extending through said last-named slot into said first-named slot, and engaging with said notches, and a spring secured to said first-named lever and bearing 40 against said catch, as set forth.

In testimony whereof I affix my signature in presence of two witnesses.

JOHN A. BELL.
